UNITED STATES PATENT OFFICE.

ANDREW D. DOWD, OF HOBOKEN, NEW JERSEY, ASSIGNEE TO WESTERN ELECTRIC COMPANY, INCORPORATED, OF NEW YORK, N. Y., A CORPORATION OF NEW YORK.

TELEGRAPH SYSTEM.

Application filed October 8, 1919. Serial No. 329,195.

To all whom it may concern:

Be it known that I, ANDREW D. DOWD, a citizen of the United States, residing at Hoboken, in the county of Hudson, State of New Jersey, have invented certain new and useful Improvements in Telegraph Systems, of which the following is a full, clear, concise, and exact description.

This invention relates to printing telegraphy and particularly to multiplex printing telegraph systems of the start-stop distributor type.

The principal objects of this invention are to provide a flexible system of communication between any number of stations, one which requires a minimum amount of maintenance and one which may readily be applied to existing circuits and be suitable for all classes of service.

20. A further object is the provision of means whereby two or more messages may be transmitted simultaneously from a single station and recorded at one or more receiving stations without employing complicated and expensive synchronizing or speed-correcting apparatus.

By means of this invention any number of stations may be interconnected and any station may serve as a transmitting station, 30 while any or all of the remaining stations may serve as receiving stations.

For the accomplishment of the above objects the invention contemplates the employment of a plurality of current control means 35 co-operating with a distributor to form units of current impulses for the line. The current control means may comprise an automatic tape transmitter or a direct keyboard transmitter, either of which may cooperate

40 with the sending distributor to form characteristic groups of current permutations.

A receiving distributor is also provided at each receiving station which operates in isochronism with the sending distributor and cooperates with an electro-mechanism to distribute the effects of the line current impulse to a suitable selecting mechanism. Applicant provides distributors with independent brushes for sending and receiving, each brush being stopped automatically, once per revolution, thereby insuring restoration to synchronism at regular intervals. Applicant's system is especially adapted to operate on circuits including several stations and it permits a

greater variation in the speed of the distributors than is permissible on multiplex circuits where a high degree of unison is required between distributors, consequently it is less difficult and less expensive to maintain.

The above and other objects of this invention will be fully set forth in the following description and claims and will be more readily understood by reference to the accompanying drawings wherein Fig. 1 represents one specific embodiment of the invention in which five signaling units are required for the transmission of each character and two additional impulses, one for starting the distributor, and the other for stopping or arresting the distributor; and Fig. 2 shows a modification of Fig. 1 wherein only one additional segment, instead of two, is required for releasing and arresting the distributor.

The system of this invention is here shown adapted for use with a code composed of units of positive and negative current impulses, but obviously other codes may be used without departing from the spirit of the invention. The system preferably employs a metallic line conductor with the usual ground return and with polar duplex equipment at each station.

Each of the accompanying drawings discloses a transmitting and receiving arrangement such as may be employed at a single station. It is readily apparent that any number of stations similarly equipped may be interconnected and one station may be sending and all others receiving, or any two stations may transmit and receive simultaneously.

In the accompanying drawings A and B are two distributor faces, preferably parallel to each other, each face consisting of a plurality of segmented and continuous rings. The distributor brush arms 10 and 110 are frictionally mounted on a constantly rotating shaft which may be driven by any suitable means, for example a motor. Each arm carries a pair of brushes which are adapted to sweep over its respective distributor face and interconnect the segmented and continuous rings when the brush arm is released, as will be hereinafter explained.

At each station there is provided a plurality of transmitters 11 which control the selectively operable contacts 12, 13, 14, 15 and

16. These contacts are permanently connected to corresponding distributor segments and are adapted to be selectively operated to pick up positive and negative current from the grounded battery 17. The transmitting mechanism 11 may consist of automatic tape transmitters or direct keyboard transmitters of any suitable type.

At each receiving station there is provided 10 a suitable receiving selecting mechanism 111 which in the present drawings consists of a plurality of selecting magnets 112, 113, 114, 115 and 116. These selecting magnets may be employed to operate any suitable recording mechanism, for example they may be employed to operate selecting discs or permutation bars of a receiving printer to effect the selection of a desired character. The actual printing of a character may be effected 15 by a printing magnet (not shown), connected to a local segment 118 by means of conductor 119.

It will be understood that all distributors are adjusted to rotate approximately at the 20 same speed and the receiving distributors are each controlled from the transmitting station.

A better understanding of the system can be obtained from a description of the selection of a particular character and the various operations which take place in transmitting and recording the impulses essential for the selection of a particular character. Let it be assumed for example, that 30 the character B is to be transmitted by the transmitter 11 and that the combination of current impulses required is positive, negative, negative, positive, positive. Now if the selectively operable contacts 12 to 16 inclusive are actuated (by either an automatic tape control transmitter or a keyboard transmitter), the selectively operable contacts will be arranged to connect positive and negative batteries to the respective 35 distributor segments 22, 23, 24, 25 and 26. The key or switch 20 is now closed to initiate the operation of the sending distributor by establishing an energizing circuit through the release magnet 21 from 40 grounded battery 27, switch 20, release magnet 21, local segment 28, distributor brush 29, local ring 30, to ground. Magnet 21, upon being energized withdraws holding pawl 31 from engagement with the brush 45 arm 10, thereby permitting the brush arm to rotate due to its frictional engagement with a constantly rotating driving shaft. It will be noted from examination of distributor A, Fig. 1, that when the brush 50 arm is at rest, positive battery is connected to the line circuit L, through distributor segment 32, brush 33, ring 34, to the apex of the windings of polar relay 35, where the current divides and flows over the line 55 L and artificial line AL. The instant, how-

ever, the sending distributor brush 33 passes from segment 32 and on to segment 36, a reversal of current is sent to the line from battery 17, segment 36, brush 33, ring 34. This reversal of current is provided for the 60 purpose of initiating the operation of the distributors B at the receiving stations which will be effected by the actuation of the receiving relays 35 whereby a circuit will be completed through each receiving 65 start magnet 121 from grounded battery 37, tongue 38 of relay 35, conductor 39, receiving distributor ring 134, brush 133, segment 136, through receiving start magnet 121 to ground. The magnet 121 on being 70 energized, withdraws its holding pawl 131 from engagement with the brush arm 110. The transmitting and receiving distributor brush arms have now been released and since they are adjusted to rotate at substantially the same speed the distributor brush 33 will pass over sending segments 75 22, 23, 24, 25 and 26, sequentially, thereby connecting those segments with the distributor ring 34 while during corresponding 80 periods of time the distributor brush 133 will pass over receiving segments 122, 123, 124, 125, and 126, respectively, thereby connecting those segments with the receiving 85 distributor ring 134. Therefore, the instant distributor brush 33 engages segment 90 22, a circuit is completed from grounded battery 17, transmitter contact 12, segment 22, brush 33, ring 34, over the line circuit 95 L and through relay 35, at the receiving 100 station. If the impulse transmitted is a marking impulse the receiving relay 35 will be actuated to complete a circuit from grounded battery 37, relay tongue 38, conductor 39, receiving ring 134, brush 133, segment 122, through the winding of selecting 105 magnet 112 to ground. Thus it will be seen that as the receiving distributor brush 133 passes over the receiving segments 122 to 126 inclusive, the selecting 110 magnets 112 to 116 inclusive of the selecting mechanism 111 will be actuated in various combinations depending upon the 115 character of the impulses sent out from the transmitting station.

Referring to the equipment at the sending station, there is provided in connection with the transmitter 11 a magnet 40 which, for automatic tape transmission, may be utilized for the purpose of advancing the 120 tape after the transmission of each group of character impulses. This magnet is shown under the control of the distributor and may be actuated at any time after a group of impulses has been transmitted and 125 prior to the time the transmitting brush reaches the first transmitting segment assigned to that particular transmitter. When two or more transmitters are operated from one distributor face, ample time 130

is available for operating the transmitter magnet of each transmitter and permitting the contacts to settle before another group of impulses needs be transmitted.

Referring now to Fig. 2 which represents a modification of the system illustrated in Fig. 1, the sending distributor is provided with one less segment and associated therewith are means for insuring a reversal of line current so that the receiving distributors may be set in operation at any time regardless of the character of the last transmitted impulse of a particular character. The transmitters shown in Fig. 2 and also the distributor releasing mechanism and duplex equipment is similar in all respects to that shown in Fig. 1, therefore no further description of this part of the system is deemed essential. In Fig. 2 the distributor brush 33 normally stands at rest on distributor segment 50 thereby maintaining the line circuit closed from grounded battery 17, transmitter contact 16, control relay 52, segment 50, brush 33, distributor ring 34, to the line L. As will be noted from the drawing the character of the current applied to the line when the distributor is at rest will depend upon whether the transmitter contact 16 is actuated or unactuated, that is whether it is in engagement with its upper or lower contact. The character of current connected to segment 51 is also dependent upon the position of the tongue of control relay 52. If the transmitter contact 16 is in engagement with its lower contact, the positive pole of battery 17 will be connected to the line L, and consequently the tongue 53 of control relay 52 will be in engagement with its lower contact thereby connecting the negative pole of battery 17 to the adjacent segment 51, so that if positive battery is connected to the line circuit L when the distributor brush rests on segment 50, current of opposite potential will be applied to the line L the instant the brush arm is released and the brush engages segment 51 thereby sending out a reversal of line current to initiate the operation of the receiving distributor. Referring to the receiving distributor Fig. 2, if it is assumed that the last impulse transmitted is of the character shown connected to transmitter contact 16, then the relay tongue 153 of control relay 152 will be in the position indicated in the drawing; consequently the start magnet 121 will remain inert until the sending distributor brush 33 has passed from segment 50 on to segment 51 thereby sending out a reversal of current to complete an energizing circuit for the start magnet 121 from grounded battery 37, relay tongue 38, conductor 39, distributor ring 134, brush 133, segment 136, release magnet 121, tongue 153 of control relay 152 to ground. It is immaterial

whether positive or negative current is applied to the line circuit L while the sending brush 33 rests on segment 50, but it is important that the condition of the line or the character of current on the line when the distributor brush 33 connects segment 51 by just the reverse of the line condition or the current on the line when the distributor brush rests on segment 50. The purpose of this arrangement is to insure that the condition of the line circuit will be altered the instant the sending distributor is set in motion in order that the receiving distributor may be released immediately to distribute the impulses from the transmitting station. The control relay 152 is provided with two windings, the circuit of one winding being controlled from a local segment 154 on the distributor B, the other winding having one terminal connected to the receiving segment 126 and controlled by the last signaling impulse of a character group. The relay 152 is arranged so that its tongue 153 will be in a position corresponding to the tongue 38 of relay 35 at the completion of each revolution. This insures an energizing circuit for the receiving start magnet 121 whenever the receiving relay is actuated to move its contact tongue from one contact to the other.

While in the accompanying drawings only two transmitting and two receiving instruments are illustrated at each station, it will be understood that any number of transmitters may operate to line L through the distributor A and a corresponding number of receiving instruments may be associated with the distributor B.

This system is suitable for use where two or more channels of communication are required and where it is difficult to obtain experienced help for maintenance purposes. It is far less expensive than the well-known multiplex synchronous equipment and is no less satisfactory.

While the accompanying drawings show the preferred form of applicant's invention, many changes and modifications may be made therein without departing from the spirit of the invention.

What is claimed is:

1. A printing telegraph system comprising a transmitting rotary distributor, a plurality of groups of conductive segments on said distributor, a plurality of groups of circuit controllers, one controller individual to each segment, means for impressing a signaling impulse upon each of said segments upon the operation of said circuit controllers, a receiving rotary distributor having a plurality of groups of segments, printing telegraph apparatus comprising a plurality of groups of selecting elements, means individual to each of said groups of segments on said receiving distributor and responsive to the selecting impulses trans-

mitted through the operation of said circuit controllers as distributed by said receiving distributor, and distributor controlling means associated with each of said distributors for periodically stopping and starting them, the distributor controlling means individual to the receiving distributor being controlled by impulses received from said transmitting distributor, the distributor controlling means individual to said transmitting distributor being controlled independently of said receiving distributor.

2. A printing telegraph system comprising a transmitting rotary distributor, a plurality of groups of conductive segments on said distributor, a plurality of groups of circuit controllers, one controller individual to each segment, means for impressing a signaling impulse upon each of said segments upon the operation of said circuit controllers, a receiving rotary distributor having a plurality of groups of segments, printing telegraph apparatus comprising a plurality of groups of selecting elements, means individual to each of said groups of segments on said receiving distributor and responsive to the selecting impulses transmitted through the operation of said circuit controllers as distributed by said receiving distributor, means for periodically stopping both of said distributors, means including an additional segment common to said groups of segments on said transmitting distributor and operative in an interval between the transmission of groups of signaling impulses, for causing the release of said transmitting distributor, and thereafter the release of said receiving distributor after a period of time less than that required for the transmission of a single group of signaling impulses.

3. A printing telegraph system comprising a transmitting rotary distributor, a plurality of groups of conductive segments on said distributor, a plurality of groups of circuit controllers, one controller individual to each segment, means for impressing a signaling impulse upon each of said segments upon the operation of said circuit controllers, a receiving rotary distributor having a plurality of groups of segments, printing telegraph apparatus comprising a plurality of groups of selecting elements, means individual to each of said groups of segments on said receiving distributor and responsive to the selecting impulses transmitted through the operation of said circuit controllers as distributed by said receiving distributor, means for periodically stopping both of said distributors, means including a single additional segment common to said groups of segments on said transmitting distributor, and operative in an interval between the transmission of groups of signaling impulses for caus-

ing the release of said transmitting distributor, and thereafter the release of said receiving distributor after a period of time less than that required for the transmission of a single group of signal impulses.

4. A printing telegraph system comprising a transmitting rotary distributor, a plurality of groups of conductive segments on said distributor, a plurality of groups of circuit controllers, one controller individual to each segment, means for impressing a signaling impulse upon each of said segments upon the operation of said circuit controllers, a receiving rotary distributor having a plurality of groups of segments, printing telegraph apparatus comprising a plurality of groups of selecting elements, means individual to each of said groups of segments on said receiving distributor and responsive to the selecting impulses transmitted through the operation of said circuit controllers as distributed by said receiving distributor, and distributor controlling means associated with each of said distributors for periodically stopping and starting them, one of said distributor controlling means being operated by impulses received from the other of said distributors, and the other of said distributors being operated independently of the distant distributor.

5. A printing telegraph system comprising a transmitting rotary distributor, a plurality of groups of conductive segments on said distributor, a plurality of groups of circuit controllers, one controller individual to each segment, means for impressing a signaling impulse upon each of said segments upon the operation of said circuit controllers, a receiving rotary distributor having a plurality of groups of segments, printing telegraph apparatus comprising a plurality of groups of selecting elements, means individual to each of said groups of segments on said receiving distributor and responsive to the selecting impulses transmitted through the operation of said circuit controllers as distributed by said receiving distributor, and distributor controlling means associated with each of said distributors for periodically stopping and starting them, the distributor controlling means individual to said transmitting distributor being controlled locally and periodically after the transmission of an invariable number of groups of signaling impulses in accordance with the previous setting of said circuit controllers.

6. A printing telegraph system comprising a transmitting rotary distributor having a plurality of conductive segments, said segments being concentrically arranged, a brush arm for successively engaging said segments, means for periodically stopping and starting said brush-arm, a plurality of automatic transmitters corresponding in

number to the groups of said segments, a plurality of circuit controllers for each of said transmitters, one individual to each of said segments, means for impressing a signaling impulse upon each of said segments upon the operation of said circuit controllers, and means individual to each of said transmitters responsive during the period of transmission of signaling impulses by one of said transmitters for producing a change in the circuit relationship of said circuit controllers individual to the other of said transmitters.

In witness whereof, I hereunto subscribe my name this 3rd day of October A. D., 1919.

ANDREW D. DOWD.
